UNITED STATES PATENT OFFICE.

HENRY ANDREW DORZAB, OF CALIFORNIA, MISSOURI, ASSIGNOR OF ONE-HALF TO
JACK BOWLIN, OF CALIFORNIA, MISSOURI.

DESIGN FOR AN EYESHADE.

Application filed April 7, 1928. Serial No. 26,168. Term of patent 7 years.

To all whom it may concern:

Be it known that I, HENRY ANDREW DORZAB, a citizen of the United States of America, residing in the city of California, Moniteau County, and State of Missouri, have invented a new, original, and ornamental Design for Eyeshades, of which the following is a specification, reference being had to the accompanying drawing, forming a part thereof, in which—

Fig. 1 is a top plan view of an eyeshade showing my new design, and

Fig. 2 is a side elevation of the same.

I claim:

The ornamental design for an eyeshade as shown.

In testimony whereof I have signed my name to this specification.

HENRY ANDREW DORZAB.
